Attorney.

UNITED STATES PATENT OFFICE

HENRY C. HERR, OF BUFFALO, NEW YORK, ASSIGNOR TO HERR MANUFACTURING COMPANY, INC., OF BUFFALO, NEW YORK, A CORPORATION OF NEW YORK

FLYER FOR SPINNING MACHINES AND THE LIKE

Application filed September 12, 1930. Serial No. 481,463.

This invention relates to improvements in the flyers employed in connection with spinning machines and the like.

One of its objects is the production of a flyer of this character which is designed to prevent twisting of the yarn or thread at the point where it leaves the bobbin, thus avoiding breaking of the yarn and assuring the making of a uniform quality product.

10 Another object of the invention is to so arrange the flyer wires that the twisting of the yarn takes place adjacent the eyes of the wires and prevents twisting between the flyer wires and the take-off bobbin.

15 A further object is to provide a novel and efficient flyer construction which affords a ready adjustment or change of relative angularity of the flyer wires to control the tension required for twisting the various sizes of

20 yarn.

A still further object of the invention is the provision of a simple and inexpensive means for effectually anchoring the flyer wires to the holder.

25 In the accompanying drawing:—

Figure 1 is a fragmentary front view of a portion of a spinning machine showing my improved flyer applied thereto. Figure 2 is an enlarged sectional side view of the flyer 30 mounted on the bobbin-spindle, the wires being shown by full lines in their relative operative position while running and by dotted lines in their inoperative or state of rest positions. Figure 3 is a top plan view thereof 35 corresponding to the full line position of the parts shown in Figure 2. Figure 4 is an enlarged top plan view of the holder for the flyer wires, the parts being in their partially assembled positions. Figures 5 and 6 are 40 perspective views of the complementary holder plates or members.

Similar characters of reference indicate corresponding parts throughout the several views.

45 This invention is applicable to spinning machines of any suitable and well known construction, 10 indicating a bobbin-spindle and 11 a take-off bobbin mounted thereon. The thread or yarn from each bobbin 50 tends upwardly through the eyes of a double

set of flyer wires 12 and 13 mounted on a holder or flyer-block applied to the bobbin-spindle and indicated generally by the numeral 14, and thence upwardly through a guide or centering eye 15 to a driven take-up 55 spool (not shown).

While the flyer-block, which is revolvably mounted on the spindle 10, may be of any appropriate construction, it is preferably in the form of a self-contained unit consisting 60 of an anchoring sleeve or journal 16 adapted for frictional engagement with the tapered end of the spindle, a hollow bearing member 17 loosely fitted on the sleeve to revolve thereon, and a base member or spider applied to the bearing member and to which the flyer wires 12, 13 are detachably connected. As shown in Figures 4, 5 and 6 this wire-attaching spider preferably consists of superposed plates 18 and 19 having registering central 65 openings 20, 21, the lower plate 18 having an annular flange 22 about its opening which is rolled over the edge of the companion plate-opening to hold the plates together but permit of their relative movement about the 70 axis of such openings. The spider may be held to the bearing member 17 by a pressed fit in the manner shown in Figure 2.

The flyer wires 12, 13 terminate at their outer ends in eyes 23, 24, respectively, while 75 their inner ends have angular attaching portions 25 which engage correspondingly shaped retaining grooves 26 in the opposite upper sides of the lower spider-plate 18 and are clamped in place by the shiftable top 80 plate 19. Said plate 18 is provided along its side edges with inwardly-bent flanges 27 which form arcuate grooves 28 for receiving the corresponding marginal edges of the upper plate in the manner shown in Figure 85 4. These flanges are notched at 29 in line with the wire-anchoring grooves 26 and the opposite edges of these notches constitute shoulders against which the shanks of the 90 flyer wires bear to resist their lateral displacement. In mounting the wires, the upper plate 19 is turned to the position shown in Figure 4, after which the wires are inserted in the exposed grooves 26 with their 95 angular portions 25 disposed side by side 100

therein and the upper plate turned to its clamping position shown in Figure 3. By this construction and arrangement of parts the flyer wires are reliably held against displacement and they may be readily replaced when desired in a minimum period of time.

Heretofore, the disposition of the flyer wires has been such that the path of the yarn between the centering eye 15 and the take-off bobbin 11 was in a substantially direct or slightly curved line, the curve being caused by the centrifugal force acting with the air resistance. In making the higher twisted yarns, especially by single operation, this curve and the slight angularity of the yarn in passing through the eyes of the flyer wires have resisted the torsional force but have not arrested it, therefore resulting in the actual twisting of the yarn at the point where it leaves the take-off bobbin and where the torsional force is greatest. This force is constant and spends its energy against the resistance of the turns or coils of yarn about the bobbin, and results in the adjoining or contacting yarn-turns being often twisted together and causes not only breakage of the yarn but the production of inferior and defective yarn.

In my arrangement of the flyer wires presently to be described, I eliminate the objections above set forth by preventing the twisting of the yarn below or between the wires and the take-off bobbin and also control the tension required for twisting various sizes of yarn. To this end, I preferably arrange each set of flyer wires 12, 13 in the angular spread formation shown in Figure 3, the wire 12 being straight and shorter than the companion wire 13 and having its eye substantially vertical. The longer wire 13 terminates in a depending arm 30 and its eye is disposed substantially horizontal or at right angles to the eye of the companion wire 12. When the parts are at rest, the wire 13 assumes the position shown by dotted lines in Figure 2, but when in motion and operative, it assumes the full line position shown in said figure, such position resulting from the centrifugal force created by the revolving flyer. In this operative position of the parts, it will be noted that the eyes 23, 24 of the respective wires 12, 13, are so disposed that the path of the yarn travel as it passes through these eyes is diverted out of a direct line to approximately right angles to the stretches of yarn leading to and from the eyes, which angle or offset affords an effective means of arresting the torsional force and twisting of the yarn at the eyes of the wires, and thus prevent twisting of the yarn between the flyer wires and the take-off bobbin. This angular path of the yarn may be readily changed to suit conditions by merely shortening or lengthening the straight wire 12.

65 The diversion of the yarn out of a direct

line to an angular one at the point of the eyes of the flyer wires also serves to increase the tension on the yarn and by clamping the angularity at this point in the manner above described, the tension may be changed accordingly. Such a change of tension is necessary to control the twisting of the various sizes of yarn. By regulating the length of the straight wire 12, which is the means of changing the degree of the angle of the yarn travel, it will be understood that both the twisting and the tension on the yarn are controlled by the flyer when in operation.

70 It will be observed from Figures 2 and 3, in the operative position of the parts, that the wire-eyes 23, 24 are at substantially the same elevation but at radially and circumferentially different points relative to the flyer-axis, thereby diverting the path of travel of the yarn or thread in correspondingly different planes.

75 As shown in Figure 6 the inner end of each wire-retaining groove may terminate in an alining opening 31 through which the inner ends of the flyer wires 12, 13 may extend.

80 I claim as my invention:—

1. A flyer, comprising a body including superposed, relatively movable plates of substantially the same shape in plan, one of said plates having a retaining groove adjacent its outer edge for receiving the inner end of a flyer-wire and an inwardly facing guide-way along its marginal edge intersecting said groove, and the other plate being revolvable over the companion plate to cover and uncover its groove and having its marginal edge engaging said guide-way.

85 2. A flyer, comprising a body including superposed, relatively movable plates, one of said plates having an angular-shaped retaining groove adjacent its outer edges for receiving the inner end of a flyer-wire and an inwardly-bent flange along its marginal edge forming a guide-way, the other plate having its marginal edge engaging said guide-way and revolvable over the companion plate to cover and uncover its groove, said flange having a notch therein registering with the wire-retaining groove.

90 3. A flyer, comprising a body including a pair of superposed plates guided for relative turning movement one over the other in interlocking relation, one of said plates having a wire-retaining groove of angular shape extending inwardly from its outer edge and facing the companion plate, the latter being adapted to overlie said groove in frictional clamping engagement with the wire, and means applied to said grooved plate for receiving the marginal edges of the companion plate to hold the same in its clamped position.

95 4. A flyer, comprising a body including a pair of superposed plates guided for relative turning movement one over the other in interlocking relation, one of said plates having a

wire-retaining groove of angular shape extending inwardly from its outer edge and facing the companion plate, said groove having an alining opening at its inner end through which the corresponding end of the flyer-wire is adapted to extend.

5. A flyer for spinning machines and the like, comprising a body, and pairs of flyer-wires applied to diametrically opposite sides 10 of said body having their shanks arranged acutely to each other and having their thread-engaging eyes disposed at different radial distances from the body-axis to divert the normal path of travel of the thread between its take-off and take-up points in both radial and circumferential directions relative to the flyer.

6. A flyer for spinning machines and the like, comprising a body, and a pair of flyer-wires disposed at an acute angle to each 20 other and radiating from said body with their shanks in substantially the same plane and having thread-engaging eyes thereon, said eyes being radially spaced beyond the flanged head of the bobbin and being at substantially the same elevation during the operation 25 of the machine, whereby the thread at the junction of said eyes is directed in a path of travel at approximately right angles to its leading and trailing ends.

7. A flyer, comprising a body, and flyer wires applied thereto in pairs at opposite sides of the body-axis, each pair diverging outwardly therefrom having their shanks in substantially the same plane and being of relatively 35 different lengths and terminating at their outer ends in thread-engaging eyes, the eyes of each pair of wires being arranged at different radial distances from the flyer axis.

8. A flyer, comprising a body, flyer wires 40 applied thereto in adjoining acute, angular relation on opposite sides of the flyer-axis with their attaching shanks disposed radially in substantially the same horizontal plane, one of said wires terminating at the 45 outer end in a depending arm free to flex outwardly and upwardly, and thread-engaging eyes formed at the free ends of said wires, said depending arm being adapted to flex outwardly and upwardly during the rotation 50 of the flyer to bring its thread-engaging eye outwardly of and substantially horizontally in line with the eye on the companion wire to direct the thread at approximately right angles to its normal path of travel.

9. A flyer, comprising a body including superposed plates guided for relative turning movement one over the other in interlocking relation, one of said plates having wire-retaining grooves extending inwardly from 60 its outer edges and facing the companion plate, and pairs of flyer wires applied to diametrically opposite sides of the body-axis, the wires of each pair having their shanks arranged at an acute angle to each other and having their attaching inner ends seated in

said plate groove, said wires having thread-engaging eyes at their outer ends arranged at different radial distances from the body-axis.
